UNITED STATES PATENT OFFICE.

FRANK O. CANELLA, OF MASON CITY, IOWA.

RAIL-JOINT.

1,378,009.

Specification of Letters Patent. Patented May 17, 1921.

Application filed February 23, 1921. Serial No. 447,127.

To all whom it may concern:

Be it known that I, FRANK O. CANELLA, a citizen of the United States of America, residing at Mason City, in the county of 5 Cerro Gordo and State of Iowa, have invented certain new and useful Improvements in Rail-Joints, of which the following is a specification.

This invention relates to certain new and 10 useful improvements in rail joints and has particular reference to a joint of the scarf type wherein a relatively long tapering tongue on the male section of the rail enters a relatively long tapering groove in the 15 female section of the rail with the abutting edges of the rail head and base flanges formed on reverse inclines at opposite sides of the rail to prevent the rail sections from relative perpendicular movement during 20 passage of rolling stock thereover, fish plates being secured to the opposite sides of the rail sections for securing the same together.

With the above general objects in view 25 and others that will become apparent as the nature of the invention is better understood, the same consists of the novel form, combination and arrangement of parts hereinafter more fully described, shown in the 30 accompanying drawing and claimed.

In the drawing, wherein like reference characters indicate corresponding parts throughout the several views,

Figure 1 is a fragmentary side elevational view of a rail joint constructed in accordance with the present invention, showing the reversely inclined abutting edges of the opposite sides of the rails in assembled formation;

Fig. 2 is a top plan view thereof,

Fig. 3 is a side elevational view of the end of the male section of the rail showing the relatively long scarf tongue and the reversely inclined opposite walls of the rail,

Fig. 4 is a side elevational view of the end of the female section of the rail, and

Fig. 5 is a cross sectional view taken on line V—V of Fig. 1 showing the fish plates and retaining bolt securing the rail sections 50 assembled.

Referring more in detail to the accompanying drawing, there is illustrated the assembled ends of rail sections 1 and 2 having

a scarf connection secured in assembled relation by the side fish plates 3 and the 55 bolts 4.

The male section 1 of the rail joint is shown more clearly in Figs. 2 and 3, the head and base flange portions of the rail 1 being cut away to provide a relatively long 60 tapering tongue 5 with the head and base flanges at opposite sides of the rail formed on reverse inclines 6 and 7 with the apices thereof terminating in a single transverse line at the head of the rail as shown in 65 Fig. 3.

The female section of the rail is shown more clearly in Figs. 2 and 4 as having a relatively long tapering slot 8 formed longitudinally thereof and extending through 70 the head, web and base flanges of the rail section 2 with the outer end of the slotted rail 2 having the opposite sides thereof reversely inclined as at 6' and 7' for abutting engagement with the reversely inclined 75 walls 6 and 7 of the rail section 1.

When the rail sections 1 and 2 are assembled, the tongue 5 is received in the slot 8 and the apices of the reversely inclined walls 6—7 and 6'—7' meet in a single transverse line at the head of the rail. Rolling stock in passing over the joint will be prevented from causing relative perpendicular movements of the rail sections of this particular form of engaging shoulders as the 85 reversely inclined abutting walls of the rail sections maintain true alinement of the rails and completely eliminate any relative movement thereof. The rail sections 1 and 2 have bolt passage openings 9 formed in the 90 webs and tongue portions that are adapted to be brought into registry as shown in Figs. 2 and 5 through which the fish plate

retaining bolts 4 pass as shown in Fig. 5. This form of connection will always maintain the rail sections in proper alinement to eliminate the separation of the adjacent rail ends and consequent damage thereto by rolling stock passing thereover the main feature of the invention, however, being to 100 prevent relative perpendicular movements of the rail ends at their points of connection.

While there is herein shown and described the preferred embodiment of the present 105 invention, it is nevertheless to be understood

that minor changes may be made therein without departing from the spirit and scope of the invention as claimed.

What is claimed as new is:—

- 5 1. In a rail joint of the type described, meeting rail ends having a scarf connection, the abutting ends of the rails having the opposite sides thereof reversely inclined to prevent relative perpendicular movements, and side retaining fish plates for the rail sections, the reversely inclined abutting ends having their apices meeting in a single transverse line at the head of the rail.
- 10 2. A rail joint of the type described comprising meeting rail ends, one of said ends having a relatively long tapering tongue projecting therefrom with the opposite sides of the rail end cut away and formed on reverse inclines with the apex meeting on a transverse line of the rail tread, the other rail end having a relatively long tapering slot formed therein for reception of said tongue with the outer ends thereof reversely inclined for abutting relations with
- 15 20 25 the reversely inclined end walls of the first named section, the reversely inclined end walls of said second section having their

apices terminating in a single transverse line at the head of the rail and in line with the apices of the reversely inclined walls of the first named section.

3. A rail joint of the type described comprising meeting rail ends, one of said ends having a relatively long tapering tongue projecting therefrom with the opposite sides of the rail end cut away and formed on reverse inclines with the apex meeting on a transverse line of the rail tread, the other rail end having a relatively long tapering slot formed therein for reception of said tongue with the outer ends thereof reversely inclined for abutting relations with the reversely inclined end walls of the first named section, the reversely inclined end walls of said second section having their apices terminating in a single transverse line at the head of the rail and in line with the apices of the reversely inclined walls of the first named section, fish plates at opposite sides of the rail sections, and transverse bolts extending through the fish plates and the adjacent parts of the meeting rail ends.

In testimony whereof I affix my signature.
FRANK O. CANELLA.
